UNITED STATES PATENT OFFICE.

ELMER E. RHOADS, OF LOCKMAN, IOWA.

PICK.

1,161,974.

Specification of Letters Patent. Patented Nov. 30, 1915.

Application filed February 15, 1915. Serial No. 8,296.

To all whom it may concern:

Be it known that I, ELMER E. RHOADS, a citizen of the United States, residing at Lockman, in the county of Monroe and State of Iowa, have invented certain new and useful Improvements in Picks, of which the following is a specification.

The invention provides novel means for detachably connecting a tool to its handle in a manner to admit of any play in the joint being readily taken up or the tool being quickly removed from the handle when occasion requires and also to secure a firm and rigid connection whereby the tool is enabled to withstand hard usage without becoming loose.

A further purpose of the invention is the provision of a joint between the tool and handle embodying elements which are mutually bracing with the result that the strain is equalized on all the parts, the joint being of such formation as to admit of any one of the coöperating elements being easily and readily replaced in the event of fracture or other cause rendering the joint insecure and repairs essential.

With these and other objects in view, which will readily appear as the nature of the invention is better understood, the same consists in the improved construction and novel arrangement and combination of parts which will be hereinafter fully described and particularly claimed.

In the accompanying drawings has been illustrated a simple and preferred form of the invention, it being, however, understood that no limitation is necessarily made to the precise structural details therein exhibited, but that changes, alterations and modifications within the scope of the invention as claimed may be resorted to when desired.

Referring to the drawings,—Figure 1 is a side view of the invention applied to a miner's pick. Fig. 2 is a sectional view showing more clearly the relative arrangement of the coöperating elements. Fig. 3 is a detail perspective view of the pick head. Fig. 4 is a detail perspective view of the socket. Fig. 5 is a detail perspective view of the connecting bolt. Fig. 6 is a modification showing the head provided with removable L-shaped studs.

Corresponding and like parts are referred to in the following description and indicated in all the views of the drawings by the same reference characters.

The numeral 1 designates the tool which in the present instance is shown as consisting of a pick head. The helve or handle 2 may be of any formation and is securely attached to a metal socket 3.

The tool or pick head 1 is provided at a central point with a pair of L-shaped studs, each consisting of a shank 4 and a beak 5, the latter projecting inward. These L-shaped studs may form a part of the tool or may be applied thereto in any manner to admit of ready replacement, should occasion require. Openings 6 are formed in the side of the tool or pick head provided with the L-shaped studs, such openings being disposed exterior to the studs.

The socket 3 is formed near one end with a transverse opening 7 and in the end adjacent the opening 7 with an oblong recess 8 which is in communication with the opening 7. The width of the recess 8 corresponds to the width of the L-shaped studs and the length of the recess coincides with the distance between the outer faces of the L-shaped studs. When the tool is properly applied to the socket the studs fill the recess 8 and preclude any movement between the tool and socket. Dowels 9 project from the outer end of the socket and are disposed a short distance from the ends of the recess 8. The dowels 9 are adapted to enter the openings 6 of the tool or pick head, thereby materially strengthening and bracing the joint.

The connecting means between the tool 90 and socket consist of a T-bolt 10 and nut 11. The head 12 of the T-bolt is of a size to snugly fit between the shanks 4 of the L-shaped studs and between the beaks 5 and the adjacent side of the tool. The width 95 of the head 12 corresponds to the width of the studs. The threaded shank 13 of the T-bolt passes between the beaks 5 and is adapted to project into the opening 7. It is noted that the T-bolt may be placed in position from either side of the tool by slipping the head 12 and threaded shank 13 laterally between the parts 4 and 5 comprising the L-shaped studs. When the bolt is in position the space between the parts 4 and 5 of 105 the studs is completely filled, the side faces of the head 12 coming flush with the side faces of the studs.

The nut 11 occupies the transverse opening 7 and its outer end engages under the 110 cross pieces of the socket spanning the outer end of the opening 7, thereby serving to

hold the tool in place. The nut 11 is adapted to be turned in any manner and receives the threaded shank 13 of the connecting bolt. As shown, the nut 11 is formed in 5 its sides with a plurality of openings 14 to receive a pin or like appliance when it is required to apply force to turn the nut either when tightening or loosening the same.

In assembling the parts the connecting 10 bolt is placed in position with its head 12 between the shanks 4 and beneath the beaks 5 of the L-shaped studs. The nut 11 is placed in the openings 7 of the socket after which the tool is placed in position 15 with the threaded shank 13 of the connecting bolt engaging the threaded opening of the nut 11. The nut is now turned to draw the connecting bolt and L-shaped studs into the recess 8 and after the nut has been tightened 20 the tool will be securely attached to the socket. It is noted that the spreading of the L-shaped lugs is prevented by reason of the same snugly fitting within the recess 8. It is also observed that by reason of the 25 L-shaped studs either one or both may be easily replaced at a nominal cost in the event of either one becoming disabled or unfitted for further effective service. Should the joint become loose after the tool has seen 30 service the play may be taken up and the tool tightened by turning the nut 11 so as to draw the tool more closely to the socket.

Having thus described the invention, what is claimed as new is:—

35 1. Means for connecting a tool to a handle, the same consisting of a tool provided with a pair of L-shaped studs arranged with their beaks projecting inward, a handle member having a transverse opening, and

a terminal recess intersecting with the transverse opening and of a size to snugly receive the L-shaped studs, a connecting T-bolt adapted to be slipped laterally between the L-shaped studs from either side of the tool, the sides of the head of the bolt coming flush with the sides of the L-shaped studs and the threaded shank of the bolt passing between the beaks or inner projections of the studs, and a nut disposed in the transverse opening of the handle member 40 and receiving the threaded shank of the connecting bolt.

2. Means for connecting a tool to a handle, the same comprising a tool having a pair of L-shaped studs with the beaks facing inward, said tool having openings exterior to the studs and upon the same side therewith, a handle member having a transverse opening, and an oblong terminal recess of a size to snugly receive the L-shaped 45 studs, said handle member being provided with dowels at the ends of the recess to enter the openings of the tool, a connecting T-bolt adapted to be placed between the studs by a transverse movement from either 50 side of the tool, the threaded shank of the connecting bolt passing between the beaks or inner projections of the studs, and a nut disposed in the transverse opening of the handle member 55 and receiving the thread shank of the connecting bolt.

In testimony whereof I affix my signature in presence of two witnesses.

ELMER E. RHOADS. [L. s.]
